UNITED STATES PATENT OFFICE.

SHINGO HARA, OF OAKLAND, CALIFORNIA.

INSOLE.

1,210,066.

Specification of Letters Patent. Patented Dec. 26, 1916.

Application filed March 13, 1916. Serial No. 83,793.

To all whom it may concern:

Be it known that I, SHINGO HARA, a subject of the Emperor of Japan, residing at Oakland, in the county of Alameda, and State of California, have invented new and useful Improvements in Insoles, of which the following is a specification.

This invention relates to insoles; and has for its object to produce a simplified form of such a device affording increased comfort and relief to the wearer.

I find from long experimentation that the causes of muscular rheumatism, soreness and lameness of the feet are directly attributable to the fact that the shoes worn exert a pressure at points on the feet which by nature are not intended to support any part of the weight. Anatomically the foot is shaped to support the weight at but three points, namely, at opposite sides of the ball and at the heel, whereas, the trend of arch supports and so-called natural shaped insoles is to increase the supporting area of the soles of the feet, thereby violating the laws of nature.

In my improved insole I have so shaped the parts as to provide for supporting engagement with the sole of the foot at the three points named and none other. By leaving the material thick at those points and attenuating or thinning it at other points I obtain the object sought.

My invention is exemplified in the following description and illustrated in the accompanying drawings, in which—

Figure 1 is a plan view of the underside of the insole. Fig. 2 is an elevation of the outside edge. Fig. 3 is an elevation of the inside edge. Fig. 4 is a cross section on line 4—4 of Fig. 1. Fig. 5 is a cross section on line 5—5 of Fig. 1. Fig. 6 is a view of a modification.

The insole shown is of an outline corresponding to the lowermost portion of the sole and is made of any suitable material. The ball and heel of the insole are made thicker than the other portions; the heel being thickest at the central portion 10 while the edges 11 of the same are preferably made thin in accordance with my plan of relieving all strains from the fleshy portions of the foot and confining the supporting area of the insole to the principal bones of the foot which, in the case of the heel, are centrally located. The ball of the foot being made up of five bones, the first and fifth of

which extend below the others, the thickened portion of my insole is correspondingly shaped, being longer beneath the fifth metatarsal bone, indicated at 12, and shorter beneath the first metatarsal bone indicated at 13, and slightly thinned centrally at 14 in the shape of a forwardly directed V.

The central portion of the insole is gradually tapered toward the heel, at the outer side 15, and the inner side 16, beneath the arch of the foot, is abruptly thinned or cut away entirely, inasmuch as the arch of the foot is not intended to support any weight. The toe portion 17 of the insole is attenuated or thinned more or less abruptly, thus relieving the strains from the overlying portions of the foot.

In shaping my insole I prefer to cut away the material at the underside, so that no inequalities or ridges may come in direct contact with the foot. By having the arched portion of the insole thin or cut away the pressure on the cuneiform bones is relieved and cause of much pain eliminated. I find the arch supports now in use put an unnatural strain on the structurally weak part of the foot and, in addition, cut off the free circulation of the blood. By thinning the toe portion of the insole, the edges of the heel and the other parts of the insole beneath the muscular and non-supporting portions of the foot, all muscular strains are relieved and excessive perspiration is overcome. Muscular rheumatism, where present, is also overcome in this manner.

My improved insole may be used in either new or old shoes with like results. The shoes should be worn a trifle larger where my insole is used in order to obtain the maximum of comfort.

In Fig. 6 I have shown a slight modification involving the addition of a cut-away portion 17' between the first and second toes; this being intended for use in connection with sandals where tie strips are worn between the toes.

The three points 10, 12 and 13, on the insole, are the only ones to have supporting engagement with the foot and thus, in effect, a tripod support is formed which corresponds substantially with the structure of the foot. Elsewhere the strains are relieved and the wearer enjoys the comfort and freedom of barefootedness.

Having thus described my invention, what

I claim and desire to secure by Letters Patent is—

1. An insole of uneven thickness having normally a flat upper surface, and having its maximum thickness at the heel and at two points near its edges and on a line substantially coinciding with the ball portion of the foot.
2. An insole having normally a flat upper surface, the thickness of the sole increasing gradually from the toe end of the sole toward its ball portion and increasing abruptly at this portion to its maximum.
3. An insole having a heel portion and spaced portions on the opposite sides of the ball of like thickness, and the remaining portions of the insole of lesser thickness and disposed normally and entirely in a flat plane with the upper surface of the heel and

ball portions whereby the remaining portions will be free to yield.

4. An insole having an uninterrupted flat upper surface and the under surface abruptly reduced at the forward end beneath the toes to form a toe support, the under surface being further attenuated to provide the greatest thicknesses of the insole at the center of the heel and in a forwardly directed V immediately behind the abruptly reduced forward end, the heel and ball being connected by a narrow strip.

In testimony whereof I have hereunto set my hand in the presence of two subscribing witnesses.

SHINGO HARA.
